Primary Examiner — Bridget L Eland*Assistant Examiner* — Lauren McVey*(74) Attorney, Agent, or Firm* — The Weintraub Group, P.L.C.(57) **CLAIM**

The ornamental design for a guitar body, as shown and described.

DESCRIPTION

FIG. 1 is a front elevation view of a guitar body, showing my new design;

FIG. 2 is a rear elevation view thereof;

FIG. 3 is a front elevation view thereof, shown with environment;

FIG. 4 is a front, bottom, second side perspective view thereof;

FIG. 5 is a front, top, first side perspective view thereof;

FIG. 6 is a first side elevation view thereof;

FIG. 7 is a second side elevation view thereof;

FIG. 8 is a bottom plan view thereof; and,

FIG. 9 is a top plan view thereof.

The broken lines shown in the views are for environmental purposes only and do not form part of the claimed design.

1 Claim, 7 Drawing Sheets(56)
